M. K. MAXWELL

ELECTRICAL FIXTURE

Filed Nov. 12, 1924

Patented Mar. 15, 1927.

1,620,909

UNITED STATES PATENT OFFICE.

MAYER K. MAXWELL, OF BUTTE, MONTANA.

ELECTRICAL FIXTURE.

Application filed November 12, 1924. Serial No. 749,475.

This invention relates to certain improvements in electrical fixtures and it is an object of the invention to provide a novel and improved device of this general character 5 adapted to provide illuminated ornamentation for the interior of an automobile or the like.

Another object of the invention is to provide a novel and improved device of this 10 general character which operates to provide an illuminated bouquet of artificial flowers.

A further object of the invention is to provide a novel and improved device of this 15 general character comprising a holder or container consisting of separable sections, said sections when assembled providing requisite connection with a suitable source of electrical energy and also providing means 20 for supporting or retaining the articles to be illuminated.

The invention consists in the details of construction and in the combination and arrangement of the several parts of my improved electrical fixture whereby certain 25 important advantages are attained and the device rendered simpler, less expensive and otherwise more convenient and advantageous for use, as will be hereinafter more 30 fully set forth.

The novel features of my invention will hereinafter be definitely claimed.

In order that my invention may be better understood, I will now proceed to describe the same with reference to the accompanying drawings, wherein:—

Figure 1 is a view in elevation of a fixture constructed in accordance with an embodiment of my invention;

Figure 2 is an elevational view somewhat of a diagrammatic character illustrating various parts of my improved fixture as herein disclosed in separated relation;

Figure 3 is an enlarged view partly in 45 section and partly in elevation of my improved fixture as herein disclosed with the flowers omitted;

Figure 4 is a view in top plan of the bracket comprised in my improved fixture;

Figure 5 is a fragmentary view somewhat of a diagrammatic character illustrating one of the flowers as herein comprised and the illuminating unit associated therewith.

As disclosed in the accompanying drawings, my improved device comprises a member M formed of suitable metal and resem-

bling a flower holder, said member consisting of two separable parts 1 and 2. Carried by the opposed end portions of the sections 1 and 2 are the members 3 and 4 of 60 an electrical connector of a conventional type, the member 3 being female and the member 4 male. The member 3 also embodies a circuit closer or switch of a conventional type and which is operated 65 through the medium of the push buttons 5. When the members 3 and 4 are in engagement one with the other, the sections 1 and 2 of the member M are maintained in desired assembled relation but to further 70 maintain the sections 1 and 2 in requisite assembly I dispose around the connecting end portions of said sections 1 and 2 the clamping band 6 provided adjacent its opposite sides with the inwardly disposed 75 ribs 7 seating within the circumferentially directed grooves or channels 8 provided in the sections 1 and 2.

As herein disclosed, the band 6 is of a split type and has its free ends provided with the 80 angularly disposed arms 9 with which is associated a clamping medium 9' herein disclosed as a conventional bolt and nut. The extremities of the arms 9 terminate in the outstanding feet 10 providing means whereby the band 6 together with the member M 85 may be suitably mounted upon a desired support and particularly within the body of an automobile or the like.

The male member 4 within the section 2 90 has operatively connected therewith in a well-known manner a cable 11 adapted for communication with a suitable source of electrical energy. The female member 3 has in electrical connection therewith the conductors 12 of desired length and which extend outwardly beyond the outer open end of the section 1. The conductors 12 as herein disclosed, are arranged in pairs and each of said pairs having wrapped therearound a 95 wire 14 or the like so that rigidity will be given to said conductors in close simulation of the stem of a flower, such as a rose.

Connected to the outer end portion of each 100 pair of conductors 12 is a socket 15 upon which is directly mounted an imitation flower 16, such as a rose, the petals of which being clustered around the centrally disposed bulb 17 which has requisite electrical connection with the socket 15.

With my improved fixture arranged with 110 an automobile or otherwise positioned a

highly ornamental effect is obtained and more especially that of an illuminated bouquet. While I have herein referred to the flowers as being in imitation of roses I do not wish to be understood as limiting myself in this respect as such representation may be as preferred as the main purpose of the invention is to provide an electrical fixture which affords effective and attractive illuminated ornamentation.

From the foregoing description it is thought to be obvious that an electrical fixture constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as lim-

iting myself to the precise arrangement and formation of the several parts herein shown in carrying out my invention in practice except as hereinafter claimed.

I claim:

A device of the class described comprising a body consisting of separable sections, an electric switch carried by one of the sections, means carried by the second section for connecting the switch with a source of electrical energy, and a clamping band disposed around the meeting end portions of the sections of the body for holding the same in assembled relation, the adjacent end portions of the sections of the body being provided with channels therearound, said clamping band being provided with ribs seating within said channels.

In testimony whereof I hereunto affix my signature.

MAYER K. MAXWELL
